UNITED STATES PATENT OFFICE.

FREDERICK AUGUST BERG, OF CHICAGO, ILLINOIS.

FLYING-MACHINE.

1,367,114.

Specification of Letters Patent.

Patented Feb. 1, 1921.

Application filed December 18, 1918. Serial No. 267,285.

To all whom it may concern:

Be it known that I, FREDERICK A. BERG, a citizen of the United States, and a resident of the city of Chicago, county of Cook, and State of Illinois, have invented certain new and useful Improvements in Flying-Machines, of which the following is a specification.

My invention relates to improvements in flying machines and has for its object the production of a flying machine which will be equipped with means for insuring safety of the aviator in case of accident to or disability of the flying machine.

A further object is the production of a safety mechanism for flying machines which will be of durable and economical construction and highly efficient in use.

Other objects will appear hereinafter.

The invention consists in the combinations and arrangements of parts hereinafter described and claimed.

The invention will be best understood by reference to the accompanying drawings forming a part of this specification, and in which—

Figure 1, is a top plan view of a flying machine embodying the invention,

Fig. 2, a side elevation thereof, with parts shown in section,

Fig. 3, an enlarged detail section taken on line 3—3 of Fig. 2,

Fig. 4, an enlarged detail section, illustrating the releasable connection between the outer ends of the parachutes and the body of the flying machine,

Fig. 5, an enlarged fragmental section of one of the parachute or sustaining members,

Figs. 6 and 7, sections taken on lines 6—6 and 7—7, respectively, of Fig. 5,

Figs. 8 and 9, enlarged sections taken on lines 8—8 and 9—9 of Fig. 5,

Fig. 10, a top plan view of the central portion of one of the parachutes or sustaining members,

Fig. 11, a central section of one of the parachutes or sustaining members in distended or unfolded form,

Fig. 12, an enlarged detail section taken on line 12—12 of Fig. 2,

Fig. 13, an enlarged section taken on line 13—13 of Fig. 2,

Fig. 14, a central section illustrating the clutch engagement for connecting the parachute distending or unfolding mechanism with the flying machine motor,

Fig. 15, an enlarged detail sectional view of the band used to hold each parachute in folded condition,

Fig. 16, a section taken on line 16—16 of 60 Fig. 15,

Fig. 17, a section taken on line 17—17 of Fig. 15, and

Fig. 18, a perspective view of one of the end pieces carried by the band shown in 65 Figs. 15 and 16.

The preferred form of construction, as illustrated in the drawings, comprises a flying machine or aeroplane 20, of any ordinary or preferred design, the same being 70 equipped with the usual power shaft 21 leading from the motor of the machine and to which is applied the propeller 22 thereof. The driver's or aviator's seat is shown at 23.

Provided at the upper side of the flying 75 machine is a pair of laterally spaced parachutes or sustaining members 24, each of which comprises a central rigid staff 25 secured at its inner end to a yoke 26 having bearings 27 at its ends which are rotatably 80 mounted in a supporting device 28, (see Fig. 5) which is rigidly secured to the plane of the flying machine or any other adjacent rigid structure which may be utilized for this purpose. The arrangement is such, as 85 will be seen, that the parachutes 24 are permanently fastened to the flying machine, but in such a manner as to permit of swinging in a vertical plane, extending longitudinally of the machine and about a transverse axis. 90

Each parachute consists of a plurality of spaced superposed parachute or sustaining elements 29, 30 and 31 which are of graduated size, the largest being at the top and the smallest at the bottom, as clearly seen in 95 Fig. 11. The element 29 is formed of a plurality of spaced radial ribs 32, over which is spread a suitable covering 33, said ribs being pivotally connected with a collar 34 which is anchored to the staff 25 of the 100 parachute. Coöoperating with the ribs 32 are brace rods 35, the lower or inner ends of which are pivotally connected with a collar 36 slidably mounted upon rod 25, as clearly seen in Fig. 5. Upward movement of the 105 collar 36 on staff 25 is limited by a stop collar 37.

Similarly, the sustaining element 30 comprises a plurality of spaced radial ribs 38 to which is fastened a suitable covering 39, 110 the inner ends of ribs 38 being pivotally connected with a collar 40 which is rigidly

fastened upon a sleeve 43 slidably mounted upon staff 25.

The sustaining element 31 similarly comprises spaced radial ribs 44, to which is 5 fastened a covering 45, the inner ends of said ribs being pivotally connected with a collar 46 which is rigidly secured to staff 25. Coöperating with ribs 44 are brace rods 47, the inner ends of which pivotally connect 10 with a collar 48 which is fixed to the slidably mounted sleeve 43.

Folding and unfolding of the parachute elements 29, 30 and 31 is effected by means of a pair of screws 49, the lower ends of 15 which are rotatably mounted in the yoke 26, as seen in Fig. 5. The upper ends of said screws are threaded in a collar 50 which is slidably mounted upon staff 25; the upper ends of said screws passing loosely through 20 a collar 49' which is fixed to the lower end of sleeve 43. The upper ends of screws 49 are headed so as to adapt said screws to limit upward movement of collar 49'. The collar 50 is rigidly connected by means of 25 bolts 51 with the lower end of a sleeve 52 slidably mounted upon sleeve 43, the bolts 51 passing loosely through collar 49'. The upper end of sleeve 52 is connected by bolts 53 with the lower end of a sleeve 54, which 30 is also slidably mounted upon sleeve 43. The bolts 53 pass loosely through the collar 48. The upper end of sleeve 54 is rigidly connected by means of rods 55 with a sleeve 56, which is slidably mounted upon staff 25, 35 said rods passing loosely through collars 42 and 46. The upper ends of rods 55 pass also loosely through the collar 46 and are provided with heads at their upper ends, for engagement with the upper side of said 40 collar 36.

The arrangement is such that an operative connection between the screws 49 and the various sets of brace rods coöperating with the various parachute or sustaining elements 45 is established, so that upon rotation of said screws in a direction to effect upward movement of the collar 50, said parachute or sustaining elements will be caused to unfold or distend, whereas, upon reverse rotation of 50 said screws, causing downward movement of the collar 50, said parachute or sustaining elements will be folded together. In the unfolding or distension of the parachute or sustaining elements, the collar 50, 55 in moving upwardly, engages with and causes upward movement of the collar 49', thereby effecting the desired upward movement of the sleeve 43, sleeve 52 being of course moved upwardly through the connection of the lower end thereof with collar 50 by means of bolts 51. This operation is much the same as that described and claimed in my co-pending application for parachutes, Serial No. 218,050, filed February 19, 1918, 60 no claim for this detail of the construction

being made in this application, the same having been covered in the co-pending application referred to.

In the present construction, however, the upper ends of members 52, 54 and 56 are of 70 inclined conical formation for engagement with the lower or inner ends of brace rods 47, 41 and 35, respectively, in order to effect an initial outward tilting of said brace rods prior to the upward movement of the lower 75 ends of said brace rods, which completes the distending or unfolding operation of the parachute elements.

The outer ends of the ribs of the parachute elements are connected by extensible 80 or foldable rods 57 with the collar 49', the upper end of collar 50 being inclined or conically formed for engagement with the inner terminals of said rods for the same reason as above set forth in connection with 85 the parts 52, 54 and 56. The lower or inner terminals of said rods 57 and the various brace rods are provided with rollers, as seen, to alleviate friction. The rotary movement of the screws 49 above referred to in effecting folding or unfolding of the parachute, is effected by means of gears 58 secured to the lower ends of said screws 49, said gears meshing with a double crown gear 59, carried by a shaft 60, having bearings in the 90 parts 27, as clearly seen in Fig. 5.

The inner ends of shafts 60 coöperating with the two parachutes are operatively connected with shafts 61, universal joints 62 being employed at the points of connection, 100 as seen in Fig. 12. The inner ends of shafts 61 carry bevel gears 63 which mesh with a bevel gear 64 provided upon a tubular shaft 65 mounted in the body of the flying machine, as clearly seen in Figs. 1 105 and 14. The forward end of the shaft 65 carries a friction wheel 66 adapted for engagement with a friction wheel 67, which is splined to the shaft 21 of the flying machine. Spaced from the wheel 66 for engagement 110 with the opposite side of the friction wheel 67 is a wheel 68, carried by a shaft 69 which is loosely mounted in the tubular shaft 65, the rearward end of shaft 67 terminating in a knob 70 arranged in operative proximity 115 with the driver's or aviator's seat 23. The arrangement is such that by pulling upon the knob 70, the aviator may pull the wheel 68 into engagement with wheel 67, and the latter in turn into engagement with the 120 wheel 66, a friction clutch being thus formed, establishing operative connection between the power shaft of the flying machine and the parachutes 24 for effecting unfolding thereof.

In order to permit of manual operation of the parachutes, a handle 71 is rotatably mounted upon the shaft 69, carrying a clutch member 72 adapted for engagement with a clutch member 73 provided upon shaft 65. 130

A threaded collar 74 is also provided upon clutch part 72, which is adapted to be rotated so as to engage with both of the clutch parts 72 and 73, thereby holding the clutch 5 teeth of said parts in mesh to permit of rotation in either direction, to fold or unfold the parachutes.

The outer ends of the parachute staffs 25 are rigidly connected by a pipe 75, from 10 which depends a medially positioned pipe section 76, as clearly seen in Figs. 2, 3 and 4. The lower end of the pipe 76 is provided with a slotted lug 77, adapted to engage in a socket 78 provided in member 79 15 secured to the rearward end of the body of the aeroplane. Slidably mounted in the member 79 is a spring-pressed bolt 80, adapted to releasably engage with the lug 77 in order to lock the parachutes in lowered, horizontal or inoperative position. 20 The bolt 80 is retracted through the medium of a cord 81, which extends forwardly and is connected with a lever 82 arranged in operative proximity with the aviator's seat 23, as clearly seen in Fig. 2. With this arrangement, it will be seen that release of the parachutes to permit of upward swinging thereof to operative position is effected by simply tilting the lever 82 in 25 order to retract bolt 80.

Coöperating with each of the parachutes 24 for holding the same in folded or collapsed condition, is a band 83 adapted to snugly embrace the same, as clearly seen in 30 Figs. 1 and 2. Each band 83 carries at its ends end pieces 84, as clearly seen in Figs. 15, 16, 17 and 18. The end pieces 84 are adapted to register with each other, one of 35 said pieces carrying a dowel pin 85 adapted 40 to engage with a socket 86, whereby said end pieces are held in alinement. A cord 87 connects with one of the end pieces 84 for fastening the same to one of the ribs of 45 the adjacent parachute or sustaining element 29.

Coöperating with the end pieces 84 of each band 83 is a yoke 88 provided at its inner side, at opposite ends thereof, with 50 rollers 89 and 90, which rollers are adapted 55 to engage with laterally projecting flanges 91 provided upon the end pieces 84. The arrangement is such that when said rollers 89 and 90 are engaged with the flanges 91 of the end pieces 84, the ends of the band 60 will be securely connected and thus the 65 parachute held in folded or collapsed condition. Upon withdrawal or detachment of the yoke 88, the end pieces 84 are disconnected, and thus the band released to permit of unfolding of the parachute. To prevent 70 accidental removal of the yoke 88, flanges 91 of the end pieces 84 are recessed, as at 92, for engagement with the rollers 89 and 90, as will be readily understood.

65 This removal of the yokes 88 in order to

release the bands 83 of the parachutes is effected by means of cords 93 which project rearwardly through the pipes 75 and thence downwardly through the pipe 76, said cords being then brought forwardly and connected with a manually operable drum 94, which is arranged in operative proximity with the aviator's seat 23.

With the construction set forth then, it will be seen that in the event of emergency, 75 the aviator needs only to operate drum 94 to release the parachutes for unfolding. Then the lever 82 is actuated to effect release of the parachutes for upward swinging thereof. This having been done, the 80 aviator, by simply pulling on the knob 70, may effect operative connection between the motor of the aeroplane and the parachutes to effect unfolding of the latter. In case the motor is not running, such unfolding 85 may be effected by means of the handle 71, as above described.

With an aeroplane equipped with mechanism as described, in the event of emergency, the parachutes being brought into play, will 90 serve to break the fall of the aeroplane, insuring an easy or retarded descent, thereby preventing injury to the aviator and also the machine.

While I have illustrated and described the 95 preferred form of construction for carrying my invention into effect, this is capable of variation and modification without departing from the spirit of the invention. I, therefore, do not wish to be limited to the 100 precise details of construction set forth, but desire to avail myself of such variations and modifications as come within the scope of the appended claims.

Having described my invention, what I 105 claim as new and desire to secure by Letters Patent is:—

1. The combination with a motor-driven flying machine, of a folding parachute swingingly connected therewith for emergency 110 use; and common means for utilizing the motor of said machine or hand power to unfold said parachute, substantially as described.

2. The combination with a motor-driven 115 flying machine, of a folding parachute swingingly connected therewith for emergency use; rotary means for effecting unfolding of said parachute; and means for utilizing the motor of said machine or hand power to actuate said rotary means, substantially as described.

3. The combination with a motor-driven 125 flying machine, of a folding parachute swingingly connected therewith for emergency use; means for unfolding said parachute, comprising a screw; and means for utilizing the motor of said machine, or hand power, to rotate said screw, substantially as described.

4. The combination with a motor-driven flying machine, of a folding parachute swingingly connected therewith for emergency use; means for unfolding said parachute, comprising a screw; and a train of gears operatively connecting the motor of said machine with said screw, substantially as described.
5. The combination with a motor-driven flying machine, of a folding parachute swingingly connected therewith for emergency use; means for unfolding said parachute, comprising a plurality of shiftably mounted elements operatively connected together; rotary means for actuating said shiftably mounted elements; and means for utilizing the motor of said machine, or hand power, to rotate said rotary means, substantially as described.
- 10 6. The combination with a flying machine, of a folding parachute swingingly connected therewith for emergency use, said parachute comprising a plurality of superposed sustaining elements; a plurality of shiftably mounted members for folding and unfolding said sustaining elements; and means for utilizing the motor of said machine for shifting said members, substantially as described.
- 15 7. The combination with a flying machine, of a folding parachute swingingly connected therewith for emergency use, said parachute comprising a plurality of superposed sustaining elements; a plurality of shiftably mounted members for folding and unfolding said sustaining elements; and means for utilizing the motor of said machine for shifting said members, said means comprising a manually controlled friction clutch operable from the aviator's seat of said machine, substantially as described.
- 20 8. The combination with a flying machine, of a folding parachute swingingly mounted
